UNITED STATES PATENT OFFICE.

EZRA C. FITCH, OF NEW YORK, N. Y., ASSIGNOR TO ROBBINS & APPLETON,
OF SAME PLACE.

WATCH-CASE.

SPECIFICATION forming part of Letters Patent No. 289,340, dated November 27, 1883.
Application filed February 15, 1883. (No model.)

To all whom it may concern:

Be it known that I, EZRA C. FITCH, of New York, in the county of New York and State of New York, have invented certain Improvements in Watch-Cases, of which the following is a specification.

This invention consists in making a watch-case of two layers of gold, one of which forms the outer and the other the inner surface of the case. The two layers are of different qualities of gold, the outer layer being of a higher quality than the inner, so that the external surface of the case is richer in appearance and material than the internal surface. The two qualities are so proportioned that when melted and mixed the mixture will be a standard quality of gold. For example, in a case composed of an outer layer of eighteen carat and an inner layer of twelve carat gold, the two qualities should be so proportioned as to melt to a given standard, say, of fourteen carats. The two layers of gold are joined together in the plate by rolling, and formed into watch-cases by dies or by any other suitable means.

The accompanying drawing, forming a part of this specification, represents a sectional view of a watch-case back constructed in accordance with my invention, the unshaded portion *a* representing the inner layer and the shaded portion *b* the outer layer. It will be observed that a case thus constructed is, as a whole, of a given standard of gold, and can be guaranteed as such, and at the same time presents an external surface of greater value and richness than said standard.

Filled cases have heretofore been made in three layers—viz., an outer and an inner layer of gold and an interposed layer of base metal; but the gold of both layers has been invariably of the same quality, so far as I am aware. My improved case is composed entirely of the two layers of gold differently alloyed, the outer layer being of a higher standard than the inner, as above described. By this construction I am enabled to make a watch-case having all the advantages of the different qualities of the

gold, and they are so disposed as to produce the greatest benefits. The outer layer, being of a high grade, admits of a fine finish, and is least liable to become tarnished or oxidized by handling or exposure. The inner layer of the lower grade adds to the strength and stiffness of the case, and while it is susceptible to a high polish it is more liable to become tarnished; but by my arrangement it is in such a position as not to be exposed to the same extent as the higher grade. If the high-grade gold wears away, the case will still show a gold surface at the points of wear. The two qualities of the metals have substantially the same coefficient of contraction and expansion and the same electrical potential, thereby avoiding any mechanical or galvanic action if exposed to variations of temperature or a galvanic excitant. This is not true of a case composed of two different metals—as gold and a baser metal—and is one of the objections to the use of such metal.

I claim—

1. A compound plate for watch-cases, consisting of two plates, one of gold of low standard, the other of gold of higher standard, rolled together, the relative thickness of the two plates being so adjusted with relation to their relative fineness that the compound plate shall equal gold of a predetermined standard. 70

2. A watch-case consisting of two plates, one for the inner side of lower standard, the other for the outside of higher standard, rolled together and formed into the desired shape, the relative thickness of the two plates being so adjusted with relation to their relative fineness that the compound plate shall equal gold of a predetermined standard. 75

In testimony whereof I have signed my name 80 to this specification in the presence of two subscribing witnesses.

EZRA C. FITCH.
